UNITED STATES PATENT OFFICE.

WYLLIS H. MARKLAND, OF ALTOONA, PENNSYLVANIA, ASSIGNOR TO WALTER H. FOSTER, OF NEW YORK, N. Y.

SURFACING MACHINE.

Application filed January 19, 1922. Serial No. 530,351.

My invention aims to provide an improved machine for finishing the faces of various articles of manufacture. The particular embodiment illustrated is designed for finishing triple valves of railway air brake equipment, but the invention is applicable to machines for performing various other classes of work.

The accompanying drawings illustrate a machine embodying the invention.

Fig. 1 is a side elevation of the complete machine;

Fig. 2 is a plan thereof;

Fig. 3 is a section on the line 3—3 of Fig. 2;

Fig. 4 is a horizontal section on the line 4—4 of Fig. 5;

Fig. 5 is a vertical section on the line 5—5 of Fig. 2;

Fig. 6 is a vertical section on the line 6—6 of Fig. 2;

Fig. 7 is a vertical section through one of the fixtures;

Fig. 8 is a horizontal section on the line 8—8 of Fig. 7;

Fig. 9 is a plan of the work-holder;

Fig. 10 is a vertical section of the same;

Fig. 11 is a plan of an alternative work-holder;

Fig. 12 is a vertical section of one of the units for securing a reciprocating movement, illustrating a modified construction at the lower end:

Fig. 13 is a right hand side elevation of the same;

Fig. 14 is a horizontal section through the bracket supporting the hanger of Figs. 12 and 13;

Fig. 15 is a horizontal section on the line 15—15 of Fig. 12;

Figs. 16 and 17 illustrate in rear elevation alternative hangers;

Fig. 18 is a section and Fig. 19 a plan of an alternative style of work-holder.

Referring now to the particular machine illustrated, it comprises three sections for performing different operations which are involved in the perfect surfacing of valves and their seats; namely a reciprocating section for finishing internal seats; a rotary section for finishing external faces on valves or seats or on the reciprocating plates of the first section, and a third section for maintaining the surfacing plates of the rotary section true. The surfacing action on

the work is accompanied by a distortion of the faces of the surfacing plates and this distortion has to be corrected from time to time in order to ensure perfect work. The truing of the surfacing plates, therefore, is an essential part of the work of truing the valve faces. And the provision of a single machine in which all of the operations described can be effected is of value in ensuring the best work and economizing labor and time, and consequently expense.

The reciprocating section comprises a cross-head or cross-bar 1 which moves constantly up and down through short distances, say about an inch. It carries a series of arms 2, see Figs. 12 and 13, adjustable to various points along its length and each carrying at its end a head 3 arranged to be disconnected by an upward pull. The head 3 carries a hanger consisting of a pair of spring wires 4 from the lower ends of which there is loosely supported a rubbing plate 5 adapted to bear on the face of a work-piece which is to be surfaced.

The cross-bar 1 is supported at its ends on posts 6 which pass down through guides 7, Fig. 6, to points below the faced portion 8 of the table and which carry at their lower ends weights 9. The posts 6 have a pin and slot connection with arms 10 on a rock shaft 11 which is supported in bearings 12 on the underside of the table and has at an intermediate point an arm 13 at the end of which is a roller bearing on an eccentric or cam 14 on a shaft 15 which is driven through a clutch 16 from a sprocket wheel 17, Fig. 5, which is driven by a sprocket chain 18 running up to a sprocket wheel 19 which is continuously rotated as hereinafter described.

This section of the machine is designed to finish flat internal seats of valves and to provide a convenient surfacing device for insertion into and withdrawal from the work. There is shown in outline at the first station on the left a casing 20. The next three surfacing devices are used to act simultaneously on different parts of a casing whose outline is indicated at 21. At the third station is a part 22 to be surfaced. These different work-pieces are mounted on work-holders of suitable shapes carried on fixtures 23 which are fixed at suitable intervals on the bed 8 in the manner indicated in Figs. 7, 8, 12 and 13.

Referring first to Figs. 12 and 13, each fixture has a pair of legs 24, 25 which pass down through a slot 26 in the table and are fastened by means of screws 27. Passing up through the slot 26 are presser bars which bear against the rubbing plates 5 and which may be made of different shapes to suit the location of the work. Such presser bars are indicated at 29 and 29^a in Fig. 1. A notched strip 28 fastened on the bar at any desired height provides a rocking bearing against the rear edge of an opening in fixed plate 30 on top of the fixture. Their upper ends are pressed forward by means of springs 31 which are fast at their left hand ends to one of the legs of the base 23 and which at their forward ends engage a bar 32 extending across the forward edge of the presser bar. When it is desired to remove a valve from the machine a downward pull pulls the corresponding presser bar 29 downward until the roller in its upper end strikes the slide plate 30 on top of the fixture 23. Similarly a simple upward pull removes the rubbing plate 5. This leaves the valve free to be removed and replaced by another without stopping the machine or interfering with the finishing operations on other valves. This continuous operation is important for the reason that it permits the finishing of a number of articles at one time, removing one, and substituting a new one in its place, without interrupting the operations on the others.

The method of supporting the hangers is shown in Figs. 12 and 13. The head 3 has a stud 33 projecting from one side which is embraced by an eye in the upper end of a plate 34, fastened on by means of a screw and washer 35. The plate 33 is split at its lower end and clamped on the ends of the wires or rods 4 of the flexible part of the hanger. The upper part of the head 3 is knurled and overlies the end of the arm 2 and has fastened on its underside a pin 36 projecting through an opening in the end of the arm; which pin has a groove about it at an intermediate point engaged by a pin or ball 37, Fig. 13, which is pressed into engagement by a spring 38 and which forms an impositive lock to prevent the lifting of the pin and the head and hanger. The engagement is sufficiently strong to carry the hanger and head up and down with the bar 1. But when a piece of work is finished a forcible pull on the head 3 will disengage the pin from the pawl and permit the complete removal of the hanger and rubbing plate 5.

The reciprocating section of the machine, above described, is adapted to finish the interior seats in valve bodies or in slide valves, and in fact any seat which is flat but which owing to its construction or location inside of or back of some projecting portions of

the work cannot be finished on a flat disc. In Fig. 1, the work 20 is a valve casing with a single seat. 21 illustrates another style of valve casing with three seats; and 22 indicates a slide valve having what is called a graduating valve seat finished. The surfaces in question are previously formed as true as ordinary machine work will permit; and the purpose of this machine is to rub the faces of the work with practically flat plates or discs, generally, though not necessarily, with an interposed loose abrasive, so as to produce greater accuracy and to cause the parts when placed together to be as nearly air-tight as possible.

At the right end of the long narrow bed 8, which carries the reciprocating mechanism, is a square table 39 which carries the rotary rubbing disc for surfacing external faces on valves or other pieces of work. The rubbing action is produced by the upper face of a horizontal disc 40, Fig. 5, the work resting face downward on this disc. The disc is centered loosely on the head 41 of a shaft 42 and rests through levelling screws 43 on a plate 44 which is threaded on to the head of the shaft and screwed up against a shoulder on the same so as to be practically permanently fixed thereto; and which has a pin or screw 45 projecting upward in the circular line of the three screws 43 so as to engage one of these and act as a driver. In this way the surfacing plate 40 is accurately supported and positively driven and at the same time can be removed instantly by merely lifting it.

The parts to be surfaced (45^a, Fig. 5) are laid face downward in openings 46, Fig. 2, through a revolving work-holding plate 47 made of a size and shape to suit the work to be finished. The plate 47 overlies the surfacing plate 40, as shown in Fig. 5, and is supported and driven by an annular member 48 surrounding the surfacing plate 40 and rotated slowly in a direction the reverse of that of the surfacing plate. The plate 47 carries on its underside three pins 49 which enter holes in the supporting member 48 so as to center the plate and to permit it to be easily removed and replaced by another with openings of different design and arrangement. Thus the work-holding plates 47 are readily removable without stopping the machine. Also any piece of work can be taken out and replaced by a new one without interfering with those which are being worked on and without stopping the machine. The supporting annulus 48 is mounted at its lower end on a disc 50 which at its center has a hub 51 journaled by means of an intermediate bushing on a post 52 which rises from the fixed supporting table 39. On the underside of the plate 50 is a gear 53 with internal teeth engaging a pinion 54 on the upper end of a shaft 55 which at its low-

er end carries a pinion 56 engaging a gear 57 on the lower end of the shaft 42. Thus the supporting member 48 and the carrier plate 47 and the articles being surfaced are rotated at a reduced speed and in the opposite direction from the surfacing plate. The shaft 42 is driven through a worm gear 58 at its lower end engaged by a worm 59 on the shaft 60 which is driven from the sprocket 17, Fig. 1, through an intermediate clutch 61.

The post 52 has an eccentric bore through which the shaft 42 passes. Thus the surfacing plate rotates on an axis eccentric to that of the carrier, and the articles to be surfaced are carried around in a path eccentric to that of the surfacing plate. They are thus acted upon by practically the entire surface of the plate 40, which tends to keep the surface of the latter true for a longer time and also to produce more accurate surfacing of the work.

This rotary section of the machine is used for surfacing the external faces, or faces of articles which have no interfering upstanding walls or projections. The holders 47 can be provided with any number of openings, all alike or varying in size and shape to suit the parts to be finished. An alternative plate 47^a, Figs. 18 and 19, may be substituted for the one shown in Fig. 2, using rectangular openings 46^a for articles of corresponding shape. These figures also show indicating devices for keeping track of the comparative length of time during which the several articles have been in the machine.

When a number of parts are being finished at one time it is desirable that they be inspected at frequent intervals to prevent unnecessary finishing and loss of time. Holes 62 are provided in the carrier plate, one opposite each opening carrying the piece of work, and a marker or button 63 is placed in the hole indicating the first station to be loaded. They are loaded in succession around the center. When the first station is emptied the marker can be moved to the hole opposite the next station, indicating that this work piece is the oldest on the machine. In the case of the six stations shown, assuming the finishing time to be six minutes, one station must be emptied and refilled and the marker advanced every minute.

In the case assumed any one piece found to be inadequately surfaced can be put back and will become No. 1 station after six one minute intervals have elapsed and the succeeding five pieces have been removed and replaced. The work for which the particular machine shown is designed is to be of the maximum accuracy, not merely smooth or relieved of roughness but absolutely flat. Each piece of work, when it is thought to be done, is tested carefully and for the

slightest imperfection is put back on the surfacing machine.

The rotary surfacing plate 40 is used not only for the articles which are to be surfaced by the machine but also for the reciprocating rubbing plates 5 of the first section which have to be kept true in order that they may produce true surfaces on the work. For continuous operation in a shop devoted to this class of work a perfect product can be turned out only by maintaining perfect rubbing plates. This involves, therefore, the rubbing of the internal faces of the work as above described, the rubbing of the rubbing plates for such internal work, the rubbing of external faces on such articles as permit it and finally the rubbing of the rotating plates which are used to rub the reciprocating plates and the external faces of the work pieces.

This is done by means of a shaft 64 at the rear of the table 65, in which is a depressed circular bed 66, Figs. 2 and 3. A bracket 67 overhangs the depressed bed 66 and provides a bearing for the shaft 64 and 90 for a vertical shaft 68 which is driven from the horizontal shaft by means of a bevelled pinion and gear 69, 70. On the bottom of the bed 66 there are three levelling set screws 69 on which rests one of the rotating surfacing plates or discs 40 which are used in the second section of the machine. For the sake of distinction I have marked this 40^a in Figs. 2 and 3. The plate, through its flange 71, rests on the levelling screws 69 and one of the pins or screws 43 which project downward from the flange is engaged by one of the levelling screws 69 to prevent the disc from rotating. On top of this a second disc 40^b rests face downward, its central opening 105 fitting over a bushing 72 on a pin 73 on the end of a crank 74 on the lower end of the vertical shaft 68. The crank shaft is held down by means of a fork 75 which is inserted between the lower side of the bearing 76 and a collar 77 on the shaft which rests on a lower bearing 78. For inserting the crank pin in the disc, the fork 75 is withdrawn and the crank shaft lifted by hand. The bushing is then placed in the disc and the 110 crank pin dropped into the bushing and the fork 75 inserted to hold the shaft down. The lower disc 40^a is centralized by means of a boss 79 on the bed plate.

The rotation of the shaft causes the upper disc to rub the lower one with an eccentric motion, at the same time rotating the upper plate about its rotating center. Abrasive may be placed between the plates to increase the wearing action. The two plates wear on each other until they have both been brought to a perfect level (or until one of them has been brought to this condition if we assume that the other was level in the beginning). The fork 75 is then removed, the 125

4
crank shaft lifted and the fork placed under the collar 77 to hold it there, which stops the rotation of the shaft by unmeshing the gears and permits the removal of the upper disc, and of course of the lower one.

5 In the continuous operation of the machine three discs will be used. One will be in action on the second section of the machine and the other two will be in this third section, being trued up. As any disc will true any other, it is advisable to place the worn disc from the second section always on the bottom and to advance it to the top when another worn disc is taken from the second 10 section. In this way the three discs are constantly changing position.

6 The several parts of the machine are driven, as above explained, from the shaft 64 which may be driven by a belt in the 20 usual way through a tight and loose pulley or may be driven by means of a gear 80 engaged by a pinion 81 on the shaft of a motor 82. Ordinarily all three sections of the machine will be driven together but they may 25 be separately disconnected by means of the clutches 16 and 61 heretofore referred to and by the disengaging of the gear 70 from the pinion 69.

7 Figs. 7 and 8 illustrate a modified design 30 of the presser bars in the first section of the machine. The presser bar 83 at a point below the bed of the fixture passes through an opening in a block 84 having rounded edges 35 engaging the bar. A pin 85 projecting sideways through the bar limits the upward position of the latter by engaging the underside of the block 84. From the right hand side of the block two rods 86 extend through guide openings in the leg 25 of the fixture 40 and from the left hand side a single rod 87 extends through the leg 24. The rods 86 thus prevent the block from turning. They also carry springs 88 which bear at their rear ends against the leg 25 and at their forward ends against nuts 89 on the rods which serve to adjust the spring pressure. The rod 87 is a guide which carries a split nut 90 serving as a stop to limit the movement of the block and rod to the left by striking the leg 24. The plate 30 is fast on the fixture 23. The back pressure from the work holds the bar 83 with its rear edge in contact with the rounded rear edge of the plate 30 and with the forward edge of the opening in 55 the block 84 against the front of the bar. Thus the bar is held frictionally in place during the operation of the machine. When the rubbing block or plate 5 is lifted the roller on the upper end of the bar 83 will swing to the right. The stop 90, however, 60 will limit the movement in that direction and prevent the roller from striking the work. When the bar is to be withdrawn the operator can pull it down by the lower end 65 against the frictional resistance offered. If

the plate 5 is lifted, the bar 83 will drop automatically.

70 According to Figs. 9 and 10 a different method is illustrated of centering and driving the work-holding plate indicated at 47. A single pin 49 is used for insertion in the hole of the ring which drives the holder. Bent strips 91 are mounted on the edge at intervals forming flanges adapted to drop 75 easily over the annular driving member and to center it.

80 In Fig. 9 also I have shown a different style of holder consisting of a ring of metal with separate hooks 92 fastened thereon and projecting into the center and embracing the work on its rear side so as to carry it forward in the direction of the arrow and to permit it to be removed easily, not only by lifting, but also by giving it a slight forward movement faster than that of the hook 85 92 which carries it.

90 In Fig. 11 I have shown at 92^a a modified style of such a hook and have shown the same stamped out integrally with the ring 47^c of the plate.

95 Figs. 16 and 17 show alternative styles of rubbing plate and supporting devices for the reciprocating section of the machine. In Fig. 16 is shown the rubbing plate 5 with a rib on its back at or near the center of which are two inward recesses 93. The wires 4 have their lower ends bent inward to form trunnions 94 which are sprung into the sockets 93 and which permit the plate to pivot or rock sufficiently to align itself with the 100 surface of the work which it engages. Or the rubbing plate 5 may be provided with side ribs in which are openings 93^a and the wires 4 may be arranged close together and bent outward at their lower ends as at 94^a to 105 form pivots which are sprung into the sockets 93^a; providing a suspension similar in function to that of Fig. 16.

110 In the third section of the machine, instead of holding the lower disc fixed, arrangements may be provided for rotating or for permitting the rotation of this plate simultaneously with the rotation of the upper plate; in this way securing a wider distribution of the wear over the surfaces of the 115 plates.

120 Though I have described with great particularity of detail certain embodiments of my invention yet it is not to be understood therefrom that the invention is restricted to the particular embodiments disclosed. Various modifications thereof in detail and in the arrangement of the parts may be made by those skilled in the art without departing from the invention as defined in the following claims.

125 What I claim is—

1. A machine of the character described including in combination a rotating surface plate for surfacing the outside faces of work.

pieces, pivotally supported reciprocating rubbing plates adapted to surface faces not accessible to said rotating plate, driving connections between the rotary surfacing plate and the reciprocating rubbing plates, a quick detachable means for breaking the connection between the reciprocating rubbing plates and said driving mechanism.

2. A machine of the character described including in combination a rotating surface plate for surfacing the outside faces of work-pieces, pivotally supported reciprocating rubbing plates adapted to surface faces not accessible to said rotating plate, and driving connections between the rotary surfacing plate and the reciprocating rubbing plates.

3. A machine of the character described including in combination a rotating metallic surfacing plate loosely mounted on a vertically disposed drive shaft, means for holding the work in engagement with said plate, a carrier rotatable with said shaft and engaging abutments on the carrier and on the surfacing plate providing a quick detachable driving connection between the two, and means operatively connected with said vertical shaft in another section of the machine for truing such surface plates when they become badly worn.

4. A machine of the class described including in combination a horizontal bar having a number of arms extending therefrom, rubbing plates, flexible connections between said rubbing plates and said arms and presser bars engaging said rubbing plates.

5. A machine of the character described including in combination a horizontal bar carrying arms adjustable along the length thereof, vertical guides for said bar, means for reciprocating said bar vertically, rubbing devices suspended from said arms and means for pressing said rubbing devices against the work.

6. A machine of the class described including in combination reciprocating rubbing devices, driving means for said rubbing devices, means for yieldingly pressing said rubbing devices against the work, and rotary

mechanism operatively connected with said driving means, said rotary mechanism including a surfacing plate adapted to true the faces of said rubbing devices and means operatively connected with said driving means adapted to rub one such surface plate on another so as to true them when they become 55 badly worn.

7. A machine of the class described including in combination a reciprocating bar having a longitudinally adjustable arm secured thereto, a quick detachable head im- 60 positively locked to said arm, a rubbing device, a flexible connection between said quick detachable head and said rubbing device and means for pressing the rubbing device against the work.

8. A machine of the class described including in combination a reciprocating bar having a longitudinally adjustable arm secured thereto, a quick detachable head im- 70 positively locked to said arm, a rubbing device suspended from said head by a flexible member, a fulcrumed presser bar for holding the rubbing device against the work and a spring actuated slide tending to rock said bar on its fulcrum.

9. A machine of the class described including in combination a base having upright guides secured thereto, posts slidable in said guides, a bar carried by said posts, a plurality of arms adjustable lengthwise on 80 said bar, rubbing devices, flexible connections between said rubbing devices and said arms, spring pressed means for holding the rubbing devices against the work.

10. In a machine of the class described, a 85 vertically reciprocable supporting bar, an arm adjustably secured thereto, a rubbing device suspended from said arm, a work holder adapted to support the work in position to be acted upon by said rubbing device, a presser member fulcrumed on said work holder and engaging said rubbing device.

In witness whereof, I have hereunto signed my name.

WYLLIS H. MARKLAND.
